UNITED STATES PATENT OFFICE.

JOSEPH C. CONN, OF BOONTON, NEW JERSEY, ASSIGNEE TO CLIPPER BELT LACER COMPANY, OF GRAND RAPIDS, MICHIGAN, A CORPORATION OF MICHIGAN.

APPARATUS FOR ATTACHING BELT HOOKS TO BELTS AND THE LIKE.

Application filed December 31, 1921. Serial No. 526,340.

To all whom it may concern:

Be it known that I, JOSEPH C. CONN, a citizen of the United States, and a resident of Boonton, Morris County, State of New Jersey, have invented an Improvement in Apparatus for Attaching Belt Hooks to Belts and the like, of which the following is a specification.

The present invention relates to an improvement in apparatus for attaching belt hooks to belts and the like. One of the objects of this invention is to provide a hand operated device for applying belt hooks and the like in such a manner that the projecting ends of the hooks will be in exact alignment and relates more particularly to setting hooks that are of the type intended to accommodate a key or pintle to form a hinge connection between the connected ends 20 of the belt.

Belt hooks of the character referred to are marketed usually in gangs or cards comprising a suitable support for a plurality of hooks arranged with their respective parts 25 in alignment and spaced equal distances apart, usually the distance which is appropriate both to the size of the hooks and to the size of the belt to which the hooks are to be applied. In use, one row of hooks is applied to one end of the belt in a predetermined position and a similar row of hooks is applied to the other end of the belt in a relatively offset position with respect to the first mentioned set so that, when the ends 30 of the belt are brought together the rounded or bent outer ends or loops of the hooks secured to one end of the belt will mesh with the corresponding loops of the other end of the belt and a key or pintle is passed 35 through the intermeshed loops to form a hinge joint.

In practice, various means have been employed for attaching hooks of this character to the ends of belts. One of the objects of this invention is to provide a device which will effectively embed the penetrating ends or the prongs of the hooks in very wide or thick belting which owing to the extreme toughness of the leather or other material 50 of the belt offers great resistance to the simultaneous passage of the prongs therethrough. This resistance has in fact imposed a limitation upon the size of attaching devices which simultaneously attach hooks 55 to large belts, so that it is customary to use

smaller devices and to repeat the operation in successive sections or increments as many times, as may be necessary to attach all of the hooks required for a single edge or end of the belt. This not only takes considerable time but it also involves the danger of the hooks not being positioned evenly or, with their outer or loop ends in exact alignment. The importance of having accurate alignment will be readily understood in view of the necessity of transmitting the strain evenly on each belt hook across the entire width of the belt and of the connecting element or pintle rather than across a relatively narrow or restricted portions thereof.

The difficulties and shortcomings are obviated by using my improved apparatus which causes the hooks to be successively pressed into penetrating engagement with the belt by application of closing pressure to the hook shanks successively and in a number of increments depending upon the thickness of the belt and other considerations. In other words, instead of simultaneously pressing in the prongs of all of the hooks at one and the same time, as is now commonly done, I provide an apparatus to press the prongs of each hook independently to a predetermined degree and repeat the pressing operation over the whole set or row until the required degree of penetration of all the prongs is attained. If both the belt and the loop of the hook members are held rigidly during the entire pressing or penetrating operation, there would be a tendency of the hooks to strain the material of the belt. Accordingly, I provide my apparatus with means to hold both the belt and the hooks only until the prongs are sufficiently engaged with the belt to support it independently of other means. I then continue the pressing in of the prongs either with the belt free to move endwise or with the hooks free to move endwise uniformly to maintain alignment of the loop ends. Thus, no straining or tearing of the material is encountered as the penetration progresses and no undue strain or stress is imposed upon the apparatus employed.

By applying pressure to each hook individually, I am enabled to attach at one operation the necessary or desired number of hooks to any width of belting or other material that may be required. Further-

more, the loop ends of the extending or exposed portions of the hooks, when in attached position, will all be in exact alignment and when used to form the hinge joint between the belt ends, the tension strain will be distributed equally across the entire width of the belt through a suitable connecting member such as a key or pintle made of raw hide, bamboo, or other suitable material.

One embodiment of apparatus suitable for practicing the method hereinabove described is illustrated in the drawings accompanying the present specification and in which

15 Figure 1 is a side elevation,

Figure 2, a central longitudinal vertical section,

Figure 3, a top plan view,

Figure 4, an end view,

20 Figure 5, a detail fragmentary view in perspective of the belt engaging and retaining mechanism,

Figure 6, a view illustrating a type of hinge connection involving the use of belt hooks,

25 Figure 7, a view in perspective of one of the presser members,

Figure 8, a central transverse vertical section of the apparatus,

30 Figure 9, a fragmentary view in vertical section showing the position of the parts in readiness for operation,

Figure 10, a similar view showing the position of the parts upon the completion

35 of the attaching operation,

Figure 11, a top plan view of the rolling carriage,

Figure 12, a central longitudinal vertical section thereof, and

40 Figure 13, a diagrammatic view illustrating the operation of the presser members and their actuating means.

The apparatus illustrated in the drawings comprises broadly a suitable base or frame means for holding a belt end in effective operative position, means for supporting a plurality of belt hooks in position to have their prongs pressed into penetrating engagement with the belt end and means for pressing said prongs into penetrating engagement with the belt material. In detail, a preferred form of this apparatus includes a rigid substantially arch-shaped frame 1, having uprights supporting spaced longitudinally extending cross members which form carriage supporting and guiding ways 4, between which are located longitudinally slidable cam or wedge carriers 2, Figures 5 and 8, provided with wedge

60 cams 3 and supported and slidable upon transversely extending cross members of the frame. A bracket 5 at one end of the frame supports a pivot mounting 6 for a comb or hook holder 7, the other end of which is supported in a bearing 8 secured to a bracket

9 and locked in position by a removable pin 10.

The belt holding mechanism includes a pair of cooperating transversely slidable belt gripping members 11 also supported on the transversely extending cross members of the frame and normally held in spaced relation by springs 12 secured to said gripping members by means of the depending perforated lugs 13. The slidable members 2, provided with the wedge shaped cams 3 engaging cam surfaces 14 in the gripping members 11 slide longitudinally with respect to said members 11 and the frame work of the apparatus, said sliding members 2 being secured together at both ends by cross members 15 and 16. Thus, when the members 2 are moved longitudinally in the direction of the arrows, Figure 3, the gripping members 11 will be moved transversely toward each other and into gripping contact with an interposed article such as a belt 17 and against pressure of the springs 12. When the sliding members 2 are pulled back or moved in the opposite direction, the gripping members 11 will move away from each other thus releasing the belt 17, the outward movement of said members 11 being effected by means of the springs 12. In order to permit more effective gripping engagement between the grippers and the belt, the inner or effective belt engaging edges of the grippers are slightly grooved or otherwise deformed.

The comb or holder 7 hereinabove referred to is provided with a plurality of hook spacing members or teeth 18 forming hook receiving recesses, Figures 8, 9 and 10, having aligned perforations 20 which form in effect a continuous passageway for a locking or hook supporting rod 21 slidably movable into and out of engagement therewith. In placing or assembling the hooks for attachment, the loop ends thereof are inserted into the recesses between the teeth of the holder and the rod 21 is pushed into place so that when the holder is arranged as shown in Figures 8 to 10 inclusive, the hooks will hang suspended upon the said rod 21 in spaced relation with their shanks extended and straddling the end of the belt 17 and in position to be acted upon by presser mechanism hereinafter to be described. The comb or holder 7 being pivotally mounted at 6 may be readily swung into and out of position so that it is removable or readily accessible in order to position the hooks therein.

The attaching device as illustrated also includes cooperating sets of hook pressing members or pressers 22 each slidable transversely toward and away from the belt 17. The inner ends of each opposed pair of pressing members 22 are arranged to engage the respective opposed shanks of a single

- hook. In the illustrated embodiment of a preferred form of hook attaching apparatus, the pressers are supported upon and slide transversely across the upper surfaces of the grippers 11, the gripper actuating slide rods 2, and the bed or frame, being retained in proper transverse alignment between abutment guides 23 and 24 located at the respective ends of the sets of pressers.
- 5 10 To maintain substantial longitudinal alignment and to permit the pressers to be moved as sets, each set is provided with suitable connecting means which will permit the desired set movement without hindering a certain amount of individual movement as between adjacent pressers in the same set, said means being shown as bars or rods 25 and 26 passing through holes 27 in the pressers, Figure 7, aligned to form a substantially continuous passageway through each set. The upper or exposed edges of the pressers are cut away uniformly as at 28, to provide, when the pressers in each set are aligned, a channel for accommodating a part or parts 25 of the presser actuating mechanism herein-after to be described and to present thereto outwardly disposed contact surfaces 29 positioned to cooperate with said part or parts of the actuating mechanism.
- 30 As shown in the drawings and more particularly in Figures 8, 11 and 12, thereof, a preferred form of presser actuating mechanism includes a carriage adapted to ride upon bearings provided by the ways 4 and 35 arched so that it may readily pass back and forth above the hook holder 7 and the sliding pressers 22. The framework of the carriage comprises side plates 30 and 31, Figure 11, end braces 32 and 33 and a central brace 40 34, lugs 35 being formed on the lower corners of the plates 30 and 31 to guide the carriage and retain it in operative position on the ways 4.
- 45 Between the side plates are cooperating roll carrying members or carriers 36 and 37, having longitudinally extending right and left hand threaded holes respectively adapted to engage and receive a screw having right and left hand threaded portions 38 and 39 respectively. The brace 34 carries two depending lugs 40 and 41, shown in dotted lines, Figure 11, which are positioned between flanges 42 and 43 on the screw to prevent endwise movement thereof and to 50 maintain the carriers in central position. The carriers 36 and 37 are provided with guiding recesses or slots 44 and 45 respectively, horizontal surfaces of which engage and slide upon surfaces of guide pins 46 and 47 respectively, which are supported between the side plates 30 and 31, being retained in operative position by locking pins 48. The carriers 36 and 37 are provided with studs 49 and 50 respectively, having rolls 51 and 52 55 supported on ball bearings at their respec-

tive depending ends. In the form of device shown in the drawings, the screw passes through the studs 49 and 50 as well as through the corresponding carriers as described above, and is provided at each end 70 with a grip 52' secured in any suitable manner.

In operating my belt hook attaching device the hooks required for one end of a given belt are positioned in the hook holder 7 which is then secured in operative position as hereinabove described. The belt end is then inserted in a vertical direction between the grippers 11 until the edge passes between the spaced prongs of the hooks and bears 80 against the outer ends of the row of depending teeth or projections 18 of the comb or holder. The operator then pushes the slides 2 and the wedge portions carried thereby in a direction to move the grippers 11 into belt 85 gripping position, where they remain with no other locking required. Both sets of pressers are then pushed by hand into engagement with the hook shanks and the rolls on the carriage are positioned by rotating 90 the screw by means of the hand grips 52' so that said rolls will readily fit into the recesses or grooves 28 when the carriage is positioned on the ways 4. A relatively slight adjustment of the roll carriers by means of 95 the screw brings the rolls into contact with surfaces 29 of both sets of pressers and the pressers are initially aligned by a run of the carriage in one direction. Additional turns of the screw will serve to bring the rolls 100 closer together and as they move back and forth in rolling contact with the surfaces 29, they exert actuating pressure thereon and force the respective pressers against the hook shanks in controllable increments. As soon 105 as the points of the prongs have engaged the belt sufficiently to hold it in position without the aid of the grippers, the slides 2 will be drawn back thus permitting the grippers to release the belt, which will then hang suspended on the rod 21 by means of the loops of the hooks.

Repeated traverses or runs of the carriage, together with further turns of the roll adjusting screw will continue the penetrating 115 movement of the prongs into the belt or other material until they reach the required position, or substantially as shown in Figure 10, whereupon the roll carriage is lifted off or otherwise removed and the rod 21 is 120 withdrawn from the hook holder to release the hooks therefrom.

I claim as my invention:

1. Apparatus for attaching belt hooks to belts and the like comprising belt supporting means, means for supporting a plurality of hooks with their shanks straddling the belt and their prongs extending inwardly toward the belt, a set of hooks pressing members at one side of the belt and slid- 125 able

toward and away therefrom, each member in said set being positioned to engage and press a corresponding hook shank toward the belt, and means for actuating said members.

5 2. Apparatus for attaching belt hooks to belts and the like comprising belt supporting means, a plurality of hook pressing members movable toward and away from the belt, means for supporting a plurality of belt hooks with their shanks positioned between the presser members and the belt and with their prongs extending toward the belt, and rolling contact means for engaging said presser members to impart effective hook pressing movement thereto, including a presser member engaging roller and a carrier therefor, said roller being adjustably mounted on said carrier.

10 3. Apparatus for attaching belt hooks to belts and the like comprising belt supporting means, a plurality of hook pressing members movable toward and away from the belt, means for supporting a plurality of belt hooks with their shanks positioned between the presser members and the belt and with their prongs extending toward the belt, rolling contact means for engaging said presser members to impart effective hook pressing movement thereto, and means for adjusting said rolling contact means to vary the extent of said effective hook pressing movement of the presser members.

15 4. In apparatus for attaching belt hooks to belts and the like, the combination of belt supporting means, hook supporting means, opposed sets of hook pressing members, and means for simultaneously actuating opposed individual presser members in said sets, including opposed rollers mounted to engage the respective sets of hook pressing members.

20 5. In apparatus for attaching belt hooks to belts and the like, the combination of belt supporting means, hook supporting means, opposed sets of hook pressing members, means for simultaneously actuating opposed individual presser members in each set, and means for adjusting said actuating members to vary the extent of effective hook pressing movement of the presser members.

25 6. In apparatus for attaching belt hooks to belts and the like, the combination of means for holding the belt, hook positioning means, and means for pressing the hook prongs into the belt comprising a series of members slideable toward and away from the belt, means for successively actuating said presser members, and means for moving the presser engaging portion of said actuating means to vary the extent of effective movement of the pressers.

30 7. Apparatus for attaching belt hooks to belts and the like comprising means for supporting a plurality of belt hooks with their

prongs extended to receive a belt, a plurality of hook engaging pressure members, and means movable in a direction normal to the direction of penetration of the prongs to move the same toward and into penetrating engagement with a belt.

35 8. Apparatus for attaching belt hooks and the like comprising means for supporting a plurality of hooks with their shanks extended in belt receiving relation and means for pressing the prongs of one set of shanks toward the other set of shanks to engage a belt including a plurality of contiguous independently movable pressing members each engaging a shank of said hooks and means for effectively moving said pressing members.

40 9. In apparatus for attaching belt hooks to belts and the like, the combination of hook supporting means, opposed sets of hook pressing members, and means in rolling contact with said presser members to advance the same in effective hook pressing operation.

45 10. In apparatus for attaching belt hooks to belts and the like, the combination of opposed sets of hook pressing members and means separate therefrom and movable successively from one presser member to the next for simultaneously advancing individual opposed members of said sets toward each other.

50 11. In apparatus for attaching belt hooks to belts and the like, the combination of opposed sets of hook pressing members and means movable from one hook pressing member to the next for simultaneously advancing individual opposed members of said sets.

55 12. Apparatus for attaching belt hooks to belts and the like comprising a frame providing spaced carriage supporting ways, a carriage slidably mounted thereon and carrying spaced rollers, means for supporting belt hooks in position to engage a belt and presser members positioned to present one end toward a hook while the other end is presented in the path of one of said rollers as said carriage is moved back and forth on the ways.

60 13. Apparatus for attaching belt hooks to belts and the like comprising hook pressing members, hook supporting means, means for effectively moving said pressing means by a predetermined amount including a roller, a carrier therefor, having a slideable block upon which said roller is supported and means passing through said block for moving the same toward and away from the pressing members.

65 In testimony whereof, I have signed my name to this specification this 28th day of December, 1921.
